PROCESS OF TREATING HYDRO-CARBON OIL

Percival C. Keith, Jr., Peapack, N. J., assignor to
Gasoline Products Company, Inc., Newark,
N. J., a corporation of Delaware

Application February 10, 1934, Serial No. 710,617

2 Claims. (Cl. 196—48.)

This invention relates to processes for the treatment of hydrocarbon oils and pertains more particularly to processes for simultaneously producing lighter oils such as gasoline from the 5 heavier higher boiling oils and at the same time forming high anti-knock gasoline from the heavy naphtha or other charging stock of a gasoline nature.

It is an object of my invention to provide a 10 process for converting a relatively heavy charging stock, such for example, as crude residuum or the like, into lighter lower boiling point oil such as gasoline, while at the same time in an interrelated series of process steps converting 15 relatively heavy naphtha or other gasoline-like oil of relatively low anti-knock value, into high anti-knock gasoline.

In accordance with my invention fresh relatively heavy charging stock, such for example 20 as crude residuum, heavy gas oil or the like, is passed in heat exchange with products of cracking produced in the process, so that the fresh charge is raised in temperature, and is then introduced into a flashing zone wherein it is further raised in temperature by contact with hot 25 vapors; a relatively heavy condensate and unvaporized portions of the relatively heavy charging stock are withdrawn from the flashing zone and, after further heat exchange with hotter 30 products of cracking, are introduced into an evaporating zone wherein partial vaporization thereof occurs by contact of the introduced oils with hot vapors rising through the evaporating zone; a mixture comprising unvaporized portions 35 of the introduced oil and condensed portions of the rising vapors is withdrawn from the evaporating zone and passed through a viscosity breaking furnace wherein the mixture is subjected to a mild cracking operation of a viscosity breaking 40 nature, and the resulting cracked products are reintroduced into the evaporating zone; vapors are passed from the evaporating zone to a separate fractionating zone wherein they are subjected to fractional condensation, the fractionated vapors 45 being removed and condensed as a desired distillate while reflux condensate is removed from the fractionating zone and passed through a separate cracking furnace in mixture with fresh heavy naphtha charging stock or the like which 50 has been preheated by indirect heat exchange with products of cracking formed in the process, the mixture of reflux condensate and fresh naphtha being subjected to cracking of a reforming nature in the cracking furnace mentioned 55 and the resulting cracked products being

introduced into the evaporating zone already mentioned. The final distillate mentioned may also be subjected to a stabilizing process if desired by being passed through a separate stabilizing zone wherein the heat necessary to carrying 5 out the stabilizing operation is derived from hot products of the cracking operation mentioned.

The above mentioned and further objects and advantages of my invention and the manner of obtaining them will be made clear in the following description taken in conjunction with the accompanying drawing.

The single figure of the drawing represents diagrammatically a cracking apparatus adapted to carry out my invention.

Referring more particularly to the drawing, reference numeral 1 indicates a charging line through which fresh relatively heavy charging stock, such for example as crude residuum, heavy gas oil or the like, is forced by pump 2, subsequently passing through indirect heat exchanger 3 into fuel oil flash tower 4, wherein it contacts with vapors rising from hot cracked products introduced at a lower point, the point of introduction of the fresh charging stock preferably 25 being intermediate a plurality of bubble trays or other fractionating devices 5. By contact with the hot rising vapors a portion of the charging stock may be vaporized, the unvaporized portion, in mixture with any condensed portion of the rising 30 vapors, being collected on trap-out tray 6, which is provided with a tall stand pipe 7 which forms, at an intermediate point in the flash tower 4, an accumulator tank or reservoir from which the mixed liquid may be withdrawn as 35 necessary. The liquid is withdrawn through pipe 8 and forced by pump 9 through indirect heat exchanger 10 into the evaporator 11, either through refluxing line 12 or through line 13, both 40 of which are provided with control valves as shown. A similar control valve may be placed around the indirect heat exchanger 10 in order to control the heat exchange operation taking place therein. The amount of oil introduced 45 through line 12 into the evaporator 11 is preferably only that necessary in order to properly reflux fractionating plates or similar devices 14, intermediate which the pipe 12 is connected. The remainder of the oil is then introduced 50 through pipe 13 directly above a trap-out tray 16, which is provided with a stand pipe 15 similarly to trap-out tray 6 in the flash tower 4. The stand-pipe 15 forms, at an intermediate point in 55 the evaporator, an accumulator tank or reservoir from which the mixed oil, comprising unvapor-

ized portions of the oil introduced through pipes 12 and 13 and condensed portions of the rising vapors, may be withdrawn for further treatment.

5 This mixed oil is withdrawn through pipe 17 and forced by pump 18 through the coils of viscosity breaking furnace or heater 19, wherein the oil is raised to a cracking temperature of, for example, 860° F. thereabouts, under an outlet pressure of, for example, from 200 to 400 pounds per square inch, and is subjected to a small amount of cracking of a viscosity breaking nature. The amount of conversion to products in the gasoline boiling range per pass of the oil 10 through the viscosity breaking furnace may be, for example, from 8% to 12%. The resulting hot cracked products pass from the furnace through line 20 having reducing valve 21 into the lower part of evaporator 11, preferably below the level 15 of the liquid therein. The pressure maintained in the evaporator may be the same or a somewhat lower pressure than that maintained at the outlet of the viscosity breaking furnace, any pressure differential being insured by action of control 20 valve 21. The pressure in the evaporator may be, for example, about 200 pounds per square inch.

In the evaporator the introduced cracked products separate into vapors and liquid residue, the former passing upwardly through the evaporator past baffle plates or other contacting elements 22, thence through stand pipe 15 and past the bubble plates or other fractionating elements 14 in the upper part of the evaporator, directly contacting the relatively heavy oil introduced 25 through pipe 12, with resulting partial condensation of the rising vapors and partial evaporation of the introduced relatively heavy oil. The vapors remaining uncondensed at the top of the evaporator pass out through vapor line 23 into bubble tower 24, wherein they are subjected to fractionation in the well known manner. Fractionated vapors pass off from the top of the bubble tower through vapor line 25 and condenser 26, the resulting condensate being collected in the receiver 27, which is also preferably held under substantially the same pressure as that of the evaporator 11 and bubble tower 24. In this separator, or receiving drum, gas separates from the liquid distillate, the former passing 30 out through vent line 28 while the latter may be withdrawn from the process through draw-off pipe 29, but is preferably instead passed to a stabilizing tower 30.

Another stream of fresh charging stock, such as heavy naphtha, natural gasoline or other gasoline like material having a relatively low anti-knock value, is forced through line 31, by action of pump 32, into the coils of cracking or reforming furnace 33, after having passed in any desired quantities through indirect heat exchangers 34 and 35 wherein the fresh charging stock is subjected to heating by indirect heat exchange with a side stream withdrawn from the bubble tower 24 and with liquid residue withdrawn from the evaporator 11. Control valves are provided around the heat exchangers 34 and 35, as indicated, so that the desired heat exchange action may be secured. The preheated heavy naphtha or the like is combined with reflux condensate withdrawn from the base of bubble tower 25 through pipe 36, and subjected to pressure created by pump 37, the resulting oil mixture passing through common pipe 38 into the coils 40 of cracking furnace or heater 33, wherein the

mixture is raised to a cracking temperature of, for example, in the neighborhood of 960° F., under an outlet pressure of, for example, about 800 pounds per square inch, and therein subjected to cracking and reformation such that 5 the gasoline-like components of the mixed charging stock are increased in anti-knock value and the heavier portions of the mixed charging stock are converted into lighter products in the gasoline boiling range.

The resulting cracked and reformed products pass from the furnace 33 through line 39, having reducing valve 40, into the base of evaporator 11, preferably below the level of the liquid therein. In the evaporator the cracked and reformed 15 products undergo separation into vapors and liquid residue, similarly to the cracked products from the viscosity breaking furnace 19, the vapors rising through the evaporator while the liquid residue is withdrawn therefrom through 20 line 41, having reducing valve 42, and is introduced into a low point in fuel oil flash tower 4, preferably intermediate a plurality of baffle plates or similar contacting devices 43. In this fuel oil flash tower a considerably lower pressure is 25 maintained, for example, a pressure in the neighborhood of 15 pounds per square inch, and as a result of this decreased pressure the introduced liquid residue undergoes partial vaporization through the agency of its contained heat, the vapors passing upwardly through the tower while the liquid residue is collected in the base thereof. This residue may be removed through draw-off line 44, heat exchanger 3 and cooler 45 to storage as fuel oil, valve 46 being provided so that the desired cooling action of heat exchanger 3 may be obtained and pump 47 being furnished to supply any necessary pressure in order to eject the oil, as well as to return a portion thereof through valved line 48 in any volume necessary to maintain the desired low temperature in the base of the fuel oil flash tower, to prevent coking thereof.

The vapors pass upwardly through fuel oil flash tower around the baffle plates 43 and through the stand pipe 7, in the upper portion of the flash tower being contacted with the heavy charging stock introduced through charging line 1 and being subjected to partial fractionation by contact with baffle plates or other similar fractionating elements 5. The uncondensed vapors pass off from the top of the flash tower 4 through vapor line 49, heat exchanger 50 and auxiliary cooler or condenser 51, into a receiving drum 52, from which distillate may be withdrawn through line 53 and passed, by action of pump 54, into the fuel oil flash tower through branch lines 55 and 56, for refluxing purposes, another portion being passed through line 57 and heat exchanger 58 into an intermediate point in the bubble tower 24, as a refluxing medium. The heat exchanger 50 may be by-passed if desired, as shown. A draw-off pipe 59 is furnished so that distillate may be diverted directly from the accumulator 52 and withdrawn from the process. Liquid residue 60 is withdrawn from the base of the evaporator 11 and circulated through pipe 60 and indirect heat exchangers 10 and 35, by action of pump 61, in any quantities necessary to maintain the desired low temperature in the base of the evaporator. 70 This temperature preferably should not rise above about 825° F. in order to insure that coke formation therein will not be excessive.

Line 62 is furnished so that a portion of the 75 reflux condensate formed in bubble tower 24

may be diverted from the process, if necessary, in order to establish balanced operating conditions. Cooling is supplied to the top of the bubble tower by withdrawing a stream of reflux condensate from a trap-out tray through pipe 63, passing the liquid so withdrawn through indirect heat exchanger 34, wherein it is cooled by indirect contact with relatively cool light gasoline-like charging stock, and is then returned to the top of the bubble tower in necessary quantities by action of pump 64, the quantity so returned being controlled, for example by a temperature responsive automatic valve 65. Reference numeral 66 is applied to a liquid level indicator attached to the base of the bubble tower.

It may be preferable to subject the distillate collected in the receiver 27 to stabilization, and to this end the distillate may be passed through pipe 67 and be forced by action of pump 68, through indirect heat exchanger 69, into an intermediate point in the lower portion of the stabilizer tower 30, to any one of a plurality of different inlets, as shown. In the stabilizer tower undesirably light gases are separated from liquid which it is desired to include in the final distillate, the gases passing off from the top of the stabilizer tower through line 70 and partial condenser 71 into reflux drum 72, the amount of cooling supplied by the condenser 71 being regulated by the level of the liquid in the reflux drum, as indicated diagrammatically by the apparatus interconnected by a dotted line 73. Refluxing liquid is returned from the reflux drum to the top of the stabilizer tower through line 74 by action of pump 75. In order to maintain the desired temperature in the base of the stabilizer tower a quantity of liquid is collected on trap-out tray 76, withdrawn therefrom through pipe 77, and forced by pump 78 through indirect heat exchanger 79, thence back into the base of the stabilizer tower. Reflux condensate is withdrawn from trap-out tray 80 located in the base of bubble tower 24 and passed through the other side of the indirect heat exchanger 79 in regulated quantities automatically controlled by temperature responsive valve mechanism 81. After passing through the indirect heat exchanger 79 a portion of the reflux condensate is returned under pressure generated by pump 82, through line 83 to the bubble tower 24, at an intermediate point therein, for refluxing purposes, branch line 84 being furnished for this purpose. Another portion of the cooled reflux condensate is passed through line 85 into the top of evaporator 11 as a cooling medium, the quantity being regulated as desired by control valve 86. Reference numeral 87 indicates a liquid level indicator for the base of the stabilizer tower.

Operation

In operation fresh relatively heavy charging stock, such, for example, as California reduced crude of about 16° A. P. I. gravity, is passed through the charging line 1 and heat exchanger 3 into the fuel oil flash tower 4, wherein the descending stream of fresh charging stock contacts the rising stream of hot vapors and is heated, a portion thereof perhaps being vaporized while heavier fractions of the rising vapors are condensed by the cooling action. Unvaporized portions of the fresh charging stock and condensed fractions of the rising vapors collect on the trap-out tray 6 and are withdrawn through line 8, passed through heat exchanger 10 where in they are further heated, and are introduced into the evaporator 11, a portion thereof being

utilized as the reflux and being introduced about bubble plates or other fractionating elements in the evaporator, the remainder thereof being injected directly on to the trap-out tray 16 on which collect unvaporized portions of the introduced liquid oil and condensed fractions of the hot vapors rising through the evaporator. This mixture of introduced liquid oil and condensate forms a composite charging stock for viscosity breaking furnace or heater 19, through which it is passed by way of conduit 17. In passing through the coils of the viscosity breaking furnace the heavy oil is raised to a cracking temperature of a moderate value, for example in the range of 840° to 880° F., preferably about 860° F. and is subjected to a moderate amount of cracking therein of a viscosity breaking nature, the percentage of conversion to products in the gasoline boiling range, per pass, being, for example, from 8% to 12%, preferably about 10%. The pressure at the outlet of the viscosity breaking furnace may be, for example, from 200 to 400 pounds per square inch, more or less, but is preferably in the neighborhood of 200 pounds per square inch. The resulting viscosity broken products pass through the line 20 into the base of the evaporator 11, preferably below the level of the liquid in the base thereof so that an agitating action is obtained.

In the evaporator 11 the vapors passing upwardly around baffle plates or other contacting devices 22, through the stand pipe 15 and then through bubble plates, or other devices of a similar nature, 14, at the same time being subjected to cooling action by contact with the liquid oil being introduced through pipe 12, and by contact with refluxing liquid introduced at the top of the evaporator through pipe 85. The vapors remaining uncondensed at the top of the evaporator pass through vapor line 23 into a lower level of the fractionator 24, wherein these vapors are subjected to fractionation in the usual well known manner. The fractionated vapors are removed from the top of the fractionator through pipe 25 and condenser 26, the resulting condensate being collected in the receiver 27. Reflux condensate formed in the fractionator is withdrawn through pipe 36 and passed to the coils of cracking furnace or heater 33 in mixture with fresh heavy naphtha or similar gasoline-like charging oil, which has preferably been previously preheated by passing through heat exchangers 34 and 35, respectively.

In the furnace 33 the mixture of reflux condensate and heavy naphtha is raised to a cracking temperature of a relatively high value, e. g. in the range of 900° to 1000° F. thereabouts, preferably in the neighborhood of 960° F., and is therein subjected to cracking of the heavier products and reformation of those in the gasoline boiling range. The quantity of gasoline-like products in the output from the cracking furnace 33 will be relatively high, particularly on account of the presence of the heavy naphtha or the like in the charge for the cracking furnace. The percentage of gasoline-like constituents in the cracked and reformed products emerging from the furnace will be strongly dependent upon the amount of naphtha or the like introduced through the charging line 31, with respect to the amount of reflux condensate with which it is combined. For example where the amount of naphtha and the amount of residuum charged to the process are approximately equal the percentage of gasoline in the output of the

cracking furnace 33 may be in the neighborhood of 60% to 70% or more and the quantity of reflux condensate may be about half that of the naphtha charge.

5 The operation in cracking furnace 33 is preferably so conducted that the outlet pressure of the furnace is relatively high, e. g. about 800 pounds per square inch, although pressures even lower or higher may be used. For example the 10 pressure may range from 200 pounds per square inch to 1000 pounds per square inch, more or less. The cracked and reformed products from the cracking furnace 33, after reduction in the 15 pressure thereof by action of reducing valve 40, pass into the evaporator 11 and therein undergo separation into vapors and liquid residue similarly to the products in the viscosity breaking furnace 19.

20 Liquid residue collecting in the base of the evaporator 11 is withdrawn through pipe 41, pressure reducing valve 42 and is introduced into fuel oil flash tower 4, which is maintained under a pressure considerably lower than that in the evaporator, the pressure in the flash tower being, 25 for example, in the neighborhood of 15 pounds per square inch. As a result of the reduction in pressure the introduced liquid residue undergoes separation into vapors and liquids in the fuel oil flash tower, the vapors rising upwardly 30 past the baffle plates 43 or the like, through stand pipe 7 and past the bubble trays or similar fractionating elements 5, the resulting fractionating vapors being removed from the top of the tower through vapor line 49 and heat exchanger 35 50 and cooler 51, respectively, the resulting condensate being collected in the accumulator 52. Condensate so collected is pumped back in desired quantities as reflux for the baffle plates 43 and bubble trays 5, while any remainder is directed through heat exchanger 50 into an intermediate point in the fractionator 24. The liquid so introduced into the fractionator serves as a refluxing medium and is at the same time subjected to partial vaporization, the lighter fractions passing upwardly through the fractionator 45 in vapor form and the heavier unvaporized fractions moving downwardly into the fractionator for recycling.

50 The distillate collected in the receiver 27 may be subjected to conventional stabilization in the tower 30, the heat necessary for effective stabilizing operation being obtained from the reflux condensate passing downward through the bubble tower or fractionator 24. To this end reflux condensate is collected on trap-out tray 80 and passed through the heat exchanger 79 and then returned in desired quantities as a refluxing medium to an intermediate point in the fractionator 24 and to an upper point in the evaporator 11. The gasoline distillate entering the 55 stabilizing tower 30 from the receiver 27 is pre-heated by passing all or a part thereof through heat exchanger 69, and refluxing is accomplished by returning to the top of the stabilizer tower a quantity of condensed lighter products which has 60 been collected in the receiver 72. The level of condensate in the receiver 72 is maintained constant by an automatic valve mechanism 73 which regulates the cooling action of adjustable cooler 74 automatically so as to form the necessary 65 amount of condensate.

70 The temperature in the base of the evaporator 11 is maintained at such a low value as to prevent coking by withdrawing a portion of the liquid residue therein, passing it in indirect heat ex-

change with cooler liquid in heat exchangers 10 and 35 and returning the cooled liquid to the base of the evaporator. The temperature in the base of the evaporator is preferably kept below a value of about 825° F. in order to insure a reasonable length of run without coking difficulties. A similar withdrawing and returning arrangement is provided for the base of the fuel oil flash tower 4 in order to maintain the necessary low temperature. The liquid oil withdrawn from the base of the flash tower through pipe 44 is cooled by passage through indirect heat exchanger 3, at the same time preheating the fresh heavy charging stock which also passes through the heat exchanger, and the cooled oil is then returned to the base of the flash tower through pipe 48. The character of the liquid drawn off from the base of the fuel oil flash tower may be regulated by proper adjustment of the pressure in the flash tower, this adjustment being accomplished by means of pressure reducing valve 42. The higher the pressure in the flash tower the lighter will be the character of the liquid withdrawn from the base thereof. Generally it is found desirable to maintain conditions so that a marketable fuel 25 oil will be withdrawn from this piece of apparatus. The specific pressure conditions mentioned hereinbefore will give such a fuel oil when the amount of refluxing liquid supplied to the fuel oil flash tower is properly regulated.

30 The ratio of heavy residual charging stock to the heavy naphtha charging stock may be of any desired value but preferably the quantities of residuum charging stock and heavy naphtha charging stock are approximately equal. While 35 it is ordinarily desirable to treat virgin residuum and a virgin heavy naphtha according to the present process, it is also possible successfully to operate on a charging stock which has previously been subjected to some degree of cracking. In 40 place of a residuum the heavy charge may be, for example, a heavy cracked gas oil, and the heavy naphtha may be a cracked product. If desired a product falling entirely in the gasoline boiling range may be introduced into the system for 45 reformation by passage through the cracking furnace or reforming furnace 33 but ordinarily it is more desirable to take a heavy naphtha which falls partly within the gasoline boiling range and partly within a slightly higher boiling range. A 50 suitable heavy naphtha charging stock is, for example, one having an initial boiling point of about 300° F. and an end point of about 420° to 425° F.

55 While I have described a particular embodiment of my invention for the purposes of illustration it should be understood that various modifications and adaptations thereof may be made within the spirit of the invention as set forth in the appended claims.

60 I claim:

1. The process of treating hydrocarbon oil which comprises passing fresh heavy charging stock in indirect heat exchange with liquid residue withdrawn from a flashing zone, then introducing the preheated charging stock into direct contact 65 with hot vapors rising through said flashing zone, collecting unvaporized portions of the fresh charging stock and condensed portions of the rising vapors at an intermediate point in said flashing zone, withdrawing the resulting mixture and 70 introducing it, after indirect heat exchange with liquid residue withdrawn from the base of an evaporating zone, into an upper level in said evaporating zone in direct contact with hot rising vapors, collecting unvaporized portions of the 75

introduced mixture and condensed portions of the rising vapors at an intermediate point in said evaporating zone as a composite charging stock, removing composite charging stock so formed from said evaporating zone and passing it through a first cracking zone wherein it is raised to a cracking temperature and subjected to conversion, introducing the resulting cracked products into a lower point in said evaporating zone wherein separation thereof into vapors and liquid residue occurs, said vapors passing upwardly through said evaporating tower in contact with said mixture introduced thereinto, removing uncondensed vapors from the top of said evaporating zone and fractionating them to form a final desired distillate and reflux condensate, mixing with reflux condensate so formed gasoline-like hydrocarbons of relatively low anti-knock value and passing the mixture through a second cracking zone wherein it is raised to a relatively high cracking temperature and subjected to cracking and reformation, introducing the resulting cracked

and reformed products into a low point in said evaporating zone, and passing liquid residue from said evaporating zone into a low point in said flashing zone with an accompanying reduction in pressure whereby said liquid residue undergoes 5 partial vaporization and vapors pass upwardly through said flashing zone in contact with said fresh heavy charging stock.

2. A process in accordance with claim 1 wherein fresh heavy naphtha charging stock from an external source is passed in indirect heat exchange relation with said liquid residue subsequently to the indirect heat exchange contact of said residue with the mixture of fresh charge and condensate withdrawn from said flashing zone 15 and introduction into said evaporating zone, and heavy naphtha so heated is used as a source of said gasoline-like hydrocarbons of relatively low anti-knock value which are combined with said reflux condensate for cracking. 20

PERCIVAL C. KEITH, JR.
